UNITED STATES PATENT OFFICE.

GUALTIERO POMA AND GIUSEPPE PELLEGRINI, OF MILAN, ITALY.

CHEMICAL-REDUCTION PROCESS BY MEANS OF SODIUM AMALGAM.

Application filed August 3, 1921. Serial No. 489,592.

To all whom it may concern:

Be it known that we, GUALTIERO POMA and GIUSEPPE PELLEGRINI, subjects of the King of Italy, residing at Cesano Maderno, Milan, 5 Italy, have invented certain new and useful Improvements in Chemical-Reduction Processes by Means of Sodium Amalgam, of which the following is a specification.

It is well known that among the various 10 processes or methods of industrial manufacture of caustic alkalis a large importance attaches to the electrochemical ones. Electrochemical processes may be split into two classes according as they use a single electrolytic chamber with mercury cathode or 15 two separate chambers—an anodic and a cathodic one—separated by a porous diaphragm.

To the first class belongs the Kellner-Solvay process (German Pat. N. 100,560 of 20 1898) which is the most largely used in the whole class. This process is characterized by the fact that the aqueous solution of the alkaline chloride undergoing electrolysis is made to flow between a movable mercury cathode and an anode consisting of a 25 series of graphite cylinders. The mercury used as a cathode flows on the slightly inclined bottom of the cell and after having 30 got charged with the alkaline metal that has become free through electrolysis, passes into a second cell where the amalgam comes into contact with water and is decomposed, giving rise to caustic alkali and free hydrogen. 35 The movement of the mercury and therewith the continuity of the process are secured by means of a special circular elevator. Under these conditions the mercury amalgam shows an alkaline metal percentage which generally 40 does not exceed 0.2% and the aqueous solution of the caustic alkali produced shows a degree of concentration ranging from 35 to 40%.

The object of the present invention, for 45 which protection within the meaning of the patent law is claimed, is the industrial employment of the alkaline amalgam such as is obtained in the industrial manufacture of caustic alkalis as a means for reducing organic and inorganic compound substances.

The annexed drawing shows by way of example two methods of carrying the process into practice.

Fig. 1 is a diagrammatic view of a first form of apparatus that has been designed 55 for the purpose and comprises a stirring device revolving about an horizontal axis.

Fig. 2 is a vertical center section of a second form of apparatus, in which the shaft is vertical instead of horizontal and has its 60 bottom fitted with a pulley and with suspension and driving gears adapted to impart a rapid revolving motion.

Fig. 3 is an horizontal section through 65 —x—x— in Fig. 1.

With reference to Fig. 1, —1— is the electrolytic cell proper in which the salt solution undergoing electrolysis is circulated; —2— is the cell where as a rule the amalgam decomposes itself in the presence of water, 70 giving rise to a solution of caustic alkali. The two combined cells —1— and —2— make up the Kellner-Solvay apparatus, —3—, instead, represents the cylindrical reaction apparatus into which the mercury 75 amalgam leaving the cell —1— is made to enter, thus shutting out, at least partly, the cell —2—. By means of the elevator —4— the mercury leaving —3— is again brought 80 into circulation in the Kellner-Solvay apparatus.

The reaction cylinder —3— is provided in well known manner with a very efficient stirring device, with a double wall whose intermediate space —5— permits of cooling down 85 the system or also of heating it according as may be required, with various apertures for introducing a thermometer and the various reacting substances and for extracting samples, and finally with various mercury, 90 water etc. seals.

With reference to Figs. 2 and 3 showing, as already said, a second form of the apparatus the revolving shaft —6— has platforms or discs —7— keyed to it, the discs being 95 made of any convenient material and fitted with concentric projections or teeth —8—.

Opposite the said discs are arranged as many discs —9— mounted on the elements —10— that make up the apparatus body or casing, the discs —9— being likewise provided with concentric projections or teeth —9'— coming in between the teeth —8— of the discs —7—. —6'— is the pulley driving the shaft —6—.

Between one pair, of discs —7—9— and

the next pair chambers —11—, triangular in section, are provided for circulating the steam or the hot and cold water.

The working of the apparatus is as follows:

The alkaline amalgam and the substance to be reduced, which is held in suspension in water or other solvent, are introduced into the container built up of the elements 10—10— through the holes —12— of the cover —13— and drop along the funnel-shaped incline —14— and through the annular center opening —15— on to the disc —8— which, owing to its quick rotating motion, 15 obliges them to flow by centrifugal force towards the periphery where they drop through circular slits —16— from the first disc on to the second and so on.

The said operation is repeated as many 20 times as there are elements —10— in the system. The number of the latter depends on the chemical nature of the process.

In the chamber —17—, where the arriving liquor is free from the alkaline metal, 25 the mercury along with the aqueous, alcohol aceton etc. liquids discharges itself through the holes —18—; the mercury separates itself from the rest owing to its greater specific weight and is conveyed to the 30 electrolytic tank by an ordinary elevator.

It will be understood that the apparatus shown may undergo considerable alterations in practice according as they must serve for instance to atomize the mercury 35 amalgam in the aqueous solutions that must be reduced, and it is not excluded that, in order to obtain an intimate contact between the amalgam, and the aqueous, alcoholic etc. suspensions, apparatus may be used that 40 work as multiple centrifugal pumps etc.

Some examples of reductions obtained by means of the process in question will illustrate the manner in which it may be carried into effect and its practical importance.

45 *1st Example—Preparation of hydrazobenzol from nitrobenzol.*

In to the apparatus are filled 200 litres of 50 10% solution of caustic soda and 20 kilos nitrobenzol, the amalgam is then passed into the apparatus and the stirring device started. It will soon be observed that the mercury under the energetic action of the stirring device, though dividing itself into 55 very minute drops inside of the apparatus, unites again into a solid mass as soon as it gets out of reach of the stirrer, the mass then flowing through the electrolytic cell, pipes, valves and liquid seals in a perfectly 60 regular manner.

During the first hours from the commencement of the reaction the temperature rises rapidly and can be maintained at abt. 60° C. only by means of cooling; no giving off of hydrogen is observed. Further on,

the activity of the reaction abates, so that heating through steam is required in order to keep the temperature between 60° and 70° C. When the liquor is entirely discoloured, the reaction is completed; the hydrazobenzol that has formed is then rapidly filtered and washed. If it is desired to convert hydrazobenzol into benzidine, it suffices to bring it into suspension in a strongly acid solution of hydrochloric acid, to keep the latter in ebullition for some time till complete solution and then to treat it with sodium sulphate. The precipitation of benzidine sulphate is thus obtained. The resulting efficiencies are quite satisfactory.

We wish to mention that from the filtration of hydrazobenzol a nearly pure solution of caustic soda is obtained, the amount thereof being proportional to the amount of metallic sodium employed. The said soda can be ordinarily used in a large number of cases for instance in the manufacture of soap, sodium hypochlorite etc.

From the abovesaid it appears, that, contrary to the industrial practice that has been followed up to the present, the manufacture of hydrazobenzol according to this process, in addition to nitrobenzol, requires only the hydrogen of the electrolytic baths, which in the largest number of the now existing plants is not being utilized at all. In this way therefore a product of such fundamental importance for colour chemistry as benzidine can be obtained under absolutely economical conditions.

In a similar manner orthotoluidine, di-anisidine etc. can be prepared starting from orthonitrotoluol or orthonitroanisol resp.

2nd Example—Preparation of aniline. 105

The experimental conditions of the foregoing example are repeated, saving that along with nitrobenzol pure water is filled into the apparatus. By means of a suitable device hydrochloric or sulphuric or some other acid is filled into the apparatus, the amount thereof being equivalent to the amount of metallic sodium contained in the amalgam; the solution should show a slightly acid reaction or even be neutral. The temperature rise is so rapid that it must be moderated by cooling. Nitrobenzol is thus reduced to aniline in a quantitative manner.

In a similar manner toluidines, xylidines, phenylene and toluylene diamines, naphthylamine, ammosulphonic compounds, aminoxy-aminoxy-sulphonics of aromatic hydrocarbons etc. can be prepared. Aldehyde and ketone compound nitrocarbocyclic acids etc. can be reduced.

The economical convenience of working to the present method in the cases mentioned should be examined case by case.

Many times instead of filling pure water

- and then hydrochloric or sulphuric acid into the apparatus it will be convenient to fill a solution of sodium bicarbonate or bisulphite and then, during the reaction, a stream of 5 carbonic or sulphuric anhydride in order to neutralize the forming soda. In this manner the alkalinity or acidity of the solution can be kept very low in correspondence to the degree of hydrolysis of the alkaline 10 carbonates or bisulphites, and at the end of the reaction, along with the reduced substance, considerable quantities of carbonate, bicarbonate, sulphite or bisulphites may be obtained.
- 15 The presence of bisulphite greatly assists in the reduction.

3rd Example—Preparation of paramino-phenol

- 20 In a vessel similar to the one already described but made of glazed cast iron or of an acidproof alloy or lined with a suitable enamel is filled an aqueous solution of sulphuric acid, along with nitrobenzol. The 25 temperature is raised to and then kept at 75°-80° C.

The weight proportions should be so adjusted as to again obtain a strongly acid solution at the end of the reduction.

- 30 The reduction takes place in a complete manner with formation of p-aminophenol sulphate and of small proportions of benzidine and aniline sulphate.

In a similar manner a number of photographic revealers can be obtained as well as of other products of industrial interest such as, for instance; diaminophenol, amidophenol carbocyclic acids and their ethers, the amidophenols of the quinoline series, the 40 ethers of the amidophenol derived from alkylated nitramines.

In a hydroalcoholic medium p-phenetidine can be prepared.

4th—Preparation of sodium hydrosulphite and sulphoxylates.

The method above described may be used also for obtaining inorganic products. For instance if in an apparatus like the one described a stream of sulphuric acid is led in such a quantity that for each molecule of anhydride there be present two atoms of sodium, a solution of hydrosulphite is formed which, if conveniently cooled, does not decompose and can be pursued up to saturation.

If as solvent for the sulphuric anhydride water is used, alkaline hydrosulphites are obtained either in aqueous solution or solid with crystallization water; if instead suitable organic solvents are used such as benzol or alcohol etc. anhydrous hydrosulphites are obtained.

If along with the other components formic 60 aldehyde or acetic aldehyde or acetone are

introduced into the vessel, the corresponding sulphoxylates are obtained which, like hydrosulphites, are of the highest importance in the dyeing industry.

The chemical reduction process or method 70 claimed in the present must be considered, in its complex as intended, among other purposes, to replace the electrochemical reduction process, over which obvious advantages of technical, economical and practical character may be claimed for it. The novel method is perfectly successful even in those cases where, as for hydrosulphites, the electrochemical method has given no practical results whereas on the other hand the novel 75 method as compared with the ordinary chemical reduction methods, presents all the advantages that used to be considered as characteristic and exclusive merits of the electrochemical processes.

We claim:

1. The combination of a process of reduction with the electrolytic process for industrially producing a caustic alkali, which combination comprises the steps of continuously electrolyzing a solution of an alkali metal salt under normal conditions while in contact with a mercury cathode, whereby a mercury amalgam of the alkali metal is formed, continuously bringing such amalgam into intimate contact both with water in order to obtain the caustic alkali and with an oxygen-containing organic compound capable of being reduced, and continuously carrying back the mercury to the electrolytic cell.

2. The combination of a process of reduction with the electrolytic process for industrially producing a caustic alkali, which combination comprises the steps of continuously electrolyzing a solution of an alkali metal salt under normal conditions while in contact with a mercury cathode, whereby a mercury amalgam of the alkali metal is formed, continuously bringing such amalgam into intimate contact both with water in order to obtain the caustic alkali and with a nitroaromatic compound, designed to be reduced, and continuously carrying back the mercury to the electrolytic cell.

3. The combination of a process of reduction with the electrolytic process for industrially producing a caustic alkali, which combination comprises the steps of continuously electrolyzing a solution of an alkali metal salt under normal conditions while in contact with a mercury cathode, whereby a mercury amalgam is formed, continuously bringing such amalgam into intimate contact both with water in order to obtain the caustic alkali, and with a reducible nitrogen-containing organic compound capable of being reduced, and continuously carrying back the mercury to the electrolytic cell.

4. The combination of a process of reduc-

tion with the electrolytic process for industrially producing a caustic alkali, which combination comprises the steps of continuously electrolyzing a solution of an alkali metal salt under normal conditions while in contact with a mercury cathode, whereby a mercury amalgam is formed, continuously bringing such amalgam into intimate contact both with water in order to obtain the caustic alkali, and with an inorganic substance which is difficultly reducible, and continuously carrying back the mercury to the electrolytic cell.

5. The combination of a process of reduction with the electrolytic process for indus-

trially producing a caustic alkali, which combination comprises the steps of continuously electrolyzing a solution of an alkali metal salt under normal condition, while in contact with a mercury cathode, whereby a 20 mercury amalgam of the alkali metal is formed, continuously bringing such amalgam into intimate contact both with water in order to obtain the caustic alkali and with an inorganic salt which is difficultly reducible, and continuously carrying back the mercury to the electrolytic cell. 25
